UNITED STATES PATENT OFFICE.

CHARLES W. TOMLIN, OF CHICAGO, ILLINOIS.

LUBRICATING DEVICE.

1,412,223.

Specification of Letters Patent. Patented Apr. 11, 1922.

Application filed January 9, 1920. Serial No. 350,270.

To all whom it may concern:

Be it known that I, CHARLES W. TOMLIN, a citizen of the United States, and a resident of the city of Chicago, county of Cook, and 5 State of Illinois, have invented certain new and useful Improvements in Lubricating Devices, of which the following is a specification.

My invention relates to improvements in 10 lubricating devices especially adapted for use in conjunction with air compressors, and has for its object the provision of an improved construction of this character which is simple and efficient in use, and capable of 15 economical manufacture.

Other objects will appear hereinafter.

The invention consists in the combinations and arrangements of parts hereinafter described and claimed.

20 The invention will be best understood by reference to the accompanying drawings forming a part of this specification, and in which,

Fig. 1, is a side view, shown partially in 25 section, of portions of an oil compressor equipped with a lubricating device embodying the invention, and

Fig. 2, a section taken on line 2-2 of Fig. 1.

30 The preferred form of construction, as illustrated in the drawings, comprises an oil compressor consisting of an upper cylinder 3 and a lower cylinder 4 provided with the usual pistons operated therein and connected 35 by the usual piston or connecting rod 5. The upper cylinder 3 is provided at its lower end with a suitable stuffing box 6 of any usual or desired construction. The lower cylinder 4 is provided at its top with a stuffing box member 7 surrounding the piston rod 5, and an oil 40 well member 8 is secured thereto, as shown. The oil well member 8 is provided at its bottom with an internally threaded socket 9 threaded exteriorly on the stuffing box 45 member 7 and suitable packing 10 is imprisoned by the oil well member 8 in the stuffing box 7, so that by securing the oil well member 8 in place, the packing 10 is compressed about the piston rod 5. The oil 50 well member 8 is filled with waste 11, or

other absorbent material, in contact with the piston rod 5, and an oil feed pipe 12 leads into the open upper end of the oil well 8 from an oil well 13 secured to the under side of upper cylinder 3 for constantly supplying oil thereto. By this arrangement a constant and uniform supply of oil will be applied to the piston rod 5 and the same will be adequately lubricated and wiped at each operation thereof. The oil supplied will be 60 constantly and uniformly applied to the reciprocating piston rod without waste.

While I have illustrated and described the preferred form of construction for carrying my invention into effect, this is capable of 65 variation and modification without departing from the spirit of the invention. I, therefore, do not wish to be limited to the precise details of construction set forth, but desire to avail myself of such variations and modifications as come within the scope of the appended claim.

Having described my invention, what I claim as new and desire to secure by Letters Patent is:—

75 The combination with an air compressor consisting of an upper and a lower cylinder, pistons in said cylinder, a vertical piston rod connecting said pistons; a stuffing box on the lower end of said upper cylinder and a 80 stuffing box member on the top of said lower cylinder surrounding said piston rod and filled with packing, of a co-operating stuffing box member threaded to said first mentioned stuffing box member; an oil well formed integrally with said second stuffing box member, said oil well surrounding said piston rod, being open at the top and filled with absorbent material contacting with said piston rod; and an oil supply well secured to 85 said upper cylinder arranged to deliver oil into the open top of said first-mentioned oil well, substantially as described.

90 In testimony whereof I have signed my name to this specification in the presence of 95 two subscribing witnesses.

CHARLES W. TOMLIN.
